(57) **CLAIM**

I claim the ornamental design for a round hinged capture restraint collar for primates, as shown and described.

DESCRIPTION

FIG. 1 is a perspective view of a round hinged capture restraint collar for primates, showing my new design;

FIG. 2 is a top plan view thereof;

FIG. 3 is a bottom plan view thereof;

FIG. 4 is a front elevational view thereof, the rear elevational view being a mirror image thereof;

FIG. 5 is a left-elevational view thereof; and,

FIG. 6 is a right-elevational view thereof.
